Specification of Letters Patent.

Patented Dec. 7, 1915.

Application filed November 4, 1911. Serial No. 658,492.

To all whom it may concern:

Be it known that I, WILLIAM M. BRUCE, Jr., a citizen of the United States, residing at Springfield, in the county of Clark and State of Ohio, have invented certain new and useful Improvements in Automatic Telephony, of which the following is a specification.

My invention relates to improvements in automatic telephony and especially to the construction of the automatic switches and the circuits for operating the same to effect interconnection between subscribers at an exchange without the use of operators at the exchange. It has been common to use for this purpose switches of two distinct types, one type known as the two movement or up and around switch, such as used in the so-called Strowger system and the other a flat or single movement switch, such as used in the so-called Lattig & Goodrum system.

My improvement primarily relates to a mechanism which embodies features of each of these systems; that is, while it is primarily a flat or single movement switch it has terminal connections or banks arranged in different levels with wipers to engage each and with means for preventing electrical connections with the wipers related to one bank when a connection is to be made with the terminals of another bank.

For the purpose of illustration I have shown a switch having two banks, each bank adapted to handle fifty lines or having fifty sets of terminal contacts, thus making provisions for one hundred connections in one switch, each of these banks has a set of wipers appropriated to the bank and the switch has operating mechanism for said wipers and also means for switching the wipers into or out of electrical connection so that when it is desired to make a connection in one bank, the wipers to that bank will be in electrical connection and the wipers relating to any other bank will be out of electrical connection. In this particular case, I have illustrated the switch and its electrical connections as used for a line or finder switch; that is, one in which, when a subscriber removes his telephone from the hook switch for the purpose of establishing a connection, the switch is started and automatically moved until an electrical connection is made with the ter-

55 minal of that line and carried into another switch, such as a selector or connector switch, the movements of the selector or connector switch being afterward effected by impulses sent from a suitable calling device at the subscriber's station. The invention is 60 applicable to selector or connector switches. In this system a number of switches less than the subscribers' lines are used, usually about ten per cent. or ten switches to each one hundred lines and means are also provided so that the lines are grouped, say ten lines to each switch; but the switches are so interconnected that in the event that the switch assigned to one group of lines is 65 busy, connections will be automatically extended to the other switches so that any one of the one hundred lines might use any one of the ten switches in the event that the other nine switches are busy.

In the accompanying drawings: Figure 1 75 is a diagrammatic view showing the distribution of the line groups to the different switches, there being ten groups and ten switches, five of the groups being assigned to one level or bank of each of the switches 80 and the other five groups assigned to the other level or bank of each of said switches. Fig. 2 is a diagrammatic view of the starting circuits for the switches and the means for extending the starting circuits of one 85 group to the switch of another group in the event that the switch is busy. Fig. 3 is a diagrammatic view of the starting circuit for one switch and the circuit for continuing the operation of the said switch in finding 90 the line of the calling subscriber. Fig. 4 is a diagrammatic view showing particularly the circuit for cutting out the line or starting relays when the switch has found the calling line. Fig. 5 is a diagram showing all the heretofore described circuits. Fig. 6 is a plan view of the mechanical parts of one of the switches. Fig. 7 is a 95 partial sectional elevation of the same showing the arrangement of the contacts.

It may be stated in the beginning that the particular form of switch which I have shown in connection with my invention is substantially the same as is now in use with the so-called Lattig & Goodrum system; 100 that is, one in which a series of wipers of a central shaft are adapted to be moved step by step over bank contacts or terminals by

the aid of a motor magnet with a spring attached to the shaft to return the same with its wipers to normal position when the switch is released by a release magnet and in this particular form of switch there are fifty sets of terminal or bank contacts and means for causing the switch to move step by step over an arc of a circle represented by these different contacts. In the ordinary finder switch, such as used in this system, it has been common to use four terminals for each line, two of these being assigned to the line and mate, a third forming part of the operating circuit for continuing the movement of the switch until the line is found, and a fourth for forming part of the circuit for operating the cut-off relays which cuts out the line relay when the switch has found the calling line; there is also provided on the shaft a wiper for each of these terminals; that is, there being four wipers adapted under the conditions of operation to form a part of the circuits named. In my improved system I use the same general form of switch, and the same general arrangement of operating mechanism, but I provide an additional bank of terminals and an additional set of wipers making eight rows of terminals and eight wipers instead of four as in the other case, so that I provide terminal connections in each switch bank for one hundred lines instead of fifty and I provide means in the switch and the switch circuits so arranged that when one set of wipers is in use in making connections with any one of the line contacts in one bank the wipers for the other bank are disconnected and vice versa.

Referring to Figs. 6 and 7, 1 is a ratchet wheel, mounted on a suitable shaft 2, which carries the wipers 3, 4, 5, 6 forming one set and 7, 8, 9, 10 forming the other set. These wipers are adapted to move over the sets of terminal contacts 11, 12, 13, 14 of one bank and 15, 16, 17, 18 of the other bank. The motor magnet 19 having a suitable armature carrying a pawl 21 to engage in the teeth of the ratchet 1, serves to move the switch shaft and wipers step by step when the magnet is energized and de-energized in the usual way, and the release magnet 22 serves to release the operating pawl as well as the holding pawl 23 when the switch is to be returned to normal, being moved to its normal position by the coil spring 24 attached at one end to the switch frame and the other to the shaft 2. There is also provided on the frame of the switch a spring arm 25 which is termed the off-normal contact which when the switch is in its normal position is forced into engagement with contact 26 and which when the switch takes its first step, moves away from the contact 26 and engages the contact 27.

As illustrated for the purpose of this ap-

plication the operation of starting the switch to find a line of a calling subscriber in the first group of fifty lines coming into this switch will be substantially the same as in the system now in use; that is to say, there would be a certain number of switches assigned to each one hundred lines, usually about ten and the lines would be arranged in groups of ten and these groups would be multiplied into the different switches assigned to the group. Where fifty line connections only are provided for in the switch, it is usual to provide multiples for each group of ten lines into five switches but in my system where connections are made for one hundred lines in each switch the connections are multiplied into ten switches. In the known system there is a single starter wire common to each group of ten lines running to each switch with means for extending it to the other switches. In my system there are two starter wires to each switch, one for the first group of ten in the first fifty and one for the second group of ten in the second fifty for starting the switch. This general arrangement being illustrated in Fig. 1.

In the simplest form of my invention as I have illustrated it, the first ten lines in the first group of fifty are connected to the upper bank of the switch and the wipers which co-operate with these lines are normally in electrical connection with the other parts of the switch and the starter wire from this group of ten is normally in operative connection with the switch so that when a call is initiated in any one of this ten group the switch will be operated in the usual way. The ten lines of the second group of fifty are assigned to the same switch but to the other or lower bank and the wipers which co-operate with this bank are normally in in-operative condition and the starter wire is normally in inoperative connection, but means are provided by which the impulses which are sent over the starter wire, which may be termed the number 2 starter wire of the switch, cuts out the No. 1 starter wire and puts the No. 2 starter wire into operative connection to start the switch and at the same time operates an auxiliary switch by means of which all of the active circuits of the switch mechanism are shifted from the first set of wipers to the second set of wipers. This would perhaps be best understood by describing the operation of the switch in selecting the line of a calling subscriber, and the way the switch is started and its operation continued by removing the receiver from the hook switch.

In Fig. 2, *a*, *b*, *c* and *d* represent subscribers' stations in different groups assigned to the same switch, *a* being in the first group of the first fifty, *b* in the first group of the second fifty, *c* in the second group

of the first fifty and *d* in the second group of the second fifty. Closing the switch hook 28 in station *a* against contact 29 operate the line relay *a*¹ from battery *a*⁵ in the well known manner. The relay *a*¹ is thus energized and pulls up its armature spring 30 against the grounded contact 31 and thus grounds the starter wire 32 which leads to contact spring 33, thence to contact 34, wire 35, contacts 36, armature spring 37, wire 38, contact 39, armature spring 40, relay 41, battery and ground, relay 41 which I call the motor magnet relay is thus energized and its grounded armature spring 42 engages contact 43 connected to wire 44 to point 45 where the circuit divides one branch going by wire 46 to the motor magnet 19 to battery and ground. This energizes the motor magnet 19 and causes it to attract its armature which brings the operating pawl into the first notch of the ratchet wheel 1 on the switch, motor magnet armature 20 also carries contact 40 so that as it is retracted the circuit for the motor magnet relay 41 is broken at contact 39 and its armature spring 42 drops back which in turn breaks the circuit for the motor magnet at 43 and it becomes deenergized and drops back. This causes the switch to move one step which releases the grounded off-normal contact 25 and permits it to engage the contact 27 connected by wire 48 to relay 49 and thence to battery and ground. This relay 49, I call the starter wire extension relay and when energized pulls up its armature spring 33 and breaks the starter wire circuit at back contact 34. The armature spring 33 engaging with the front contact 50 causing the starter circuit to be extended to the next switch as hereinafter more fully described. When the switch is thus started the operation continues until it finds the calling line over the usual operating circuit which is not shown in Fig. 2 but which will be pointed out later.

In the event that the call should originate at station *b* by the closing of the hook switch *b*²⁸ on the contact *b*²⁹, the line relay *b*¹ would be energized from battery *b*⁵ in the manner before described, armature spring *b*³⁰ would be closed against ground contact *b*³¹ and the starter wire *b*³² thus grounded, which starter wire leads to armature spring 51 of the relay 49, and by contact 52, wire 53, point 54, to relay magnet 55, battery and ground. This energizes the relay magnet 55 which thus pulls up its armature spring 37 breaking the circuit of the starter wire *a*³² at contact 36 and closing a circuit from point 54, contact 56, armature spring 37, wire 38, contact 39, spring 40 and motor magnet relay 41 to battery and ground thus energizing the motor magnet relay 41 which in turn energizes the motor magnet 19 at and causes it to advance the switch one step as before

described, the only difference in the operation resulting from the closing of the switch hook at *b* over that at *a* being the energizing of the magnet relay 55 which cuts out the starter wire *a*³² and cuts in the starter wire *b*³². The relay magnet 55 has an additional function; that is, it operates the escapement of the two movement four wiper auxiliary switch indicated at *a*¹¹, the wipers of this auxiliary switch are connected through circuits, in the manner hereinafter described, to the line and operating circuits of the switch corresponding to the four terminals in each bank of the switch and the four sets of two contacts each of this auxiliary switch are connected by circuits, herein-after described, to the four main wipers co-operating with each switch bank so that when the auxiliary switch is moved from its first to its second position the wipers of the first bank are cut out of active operation and the wipers of the second bank are cut into active operation. When the auxiliary switch wipers are once moved to the second position they are held in this position until the switch is released when the wipers are returned to their normal or first position thus cutting in the first group and cutting out the second group of wipers for the main switch.

Having thus described the starting of switch *a*¹⁰ by a subscriber in the first group of the first fifty or the first group of the second fifty I will now explain how the starter wires are extended to the switches pertaining to the other groups so that other calls from these same groups will be transmitted to the other switch when these switches are in use.

It will be remembered that the starting circuit *a*³² and *b*³² from the respective groups pass through the armature spring 33 and 51 which are controlled by the starter extension relay 49 and that this relay 49 is energized by the off-normal contact 25 grounding the contact 27, armature spring 33 is thus caused to engage contact 50 and armature spring 51 engages contact 57; the contact 57 is connected by wire 58 to armature spring 59 and contact 50 is connected by wire 60 to armature spring 61 of a slow relay *a*⁶². Armature spring 59 engages back contact 62 and armature spring 61 engages back contact 63. From contact 63, wire 64, leads to armature spring *b*³³ in switch *b*¹⁰ which corresponds to the armature spring 33 in switch *a*¹⁰ and normally engages contact *b*³⁴ in the circuit for the motor magnet relay 41.

Contact 62 is connected by wire 65 to armature spring *b*⁵¹ in switch *b*¹⁰ which normally engages back contact *b*⁵² in the No. 2 starting circuit of switch *b*¹⁰ which is in the circuit of the relay 55 so that when the relay 49 of switch *a*¹⁰ is energized both the starter wire *a*³² and *b*³² are extended if the

relay a^{62} is in its normal or deenergized condition. These extensions are through the wires 64 and 65 to the second switch b^{10} and in the event that a call should afterward originate in the first group or group a , starter wire c^{32} would be closed to ground and being extended over wire 64 would cause the switch b^{10} to operate in the same manner as switch a^{10} heretofore described. In case 16 a call should originate in the second or b group the starter wire b^{32} would be closed to ground and would be extended over wire 65 to armature spring b^{51} and thence through relay magnet 55 which would cut 15 out the No. 1 starting circuit at contact 36 of switch b^{10} and cut in the No. 2 circuit at contact 56 of said switch and at the same time cause the auxiliary switch b^{11} to pass from its first to its second position.

20 The extension of the starting circuit from switch b^{10} into the next succeeding switch is accomplished in the same manner except that from contacts 62 and 63 of switch b^{10} wires b^{64} and b^{65} lead directly to and are 25 connected into starter wire c^{32} and d^{32} leading from the c and d groups so that in case switch c^{10} is engaged or in case all of these switches were engaged, calls from either a , b , c or d groups would go into switch d^{10} 30 over the extended starter wires c^{64} and c^{65} of the switch c^{10} which lead to the armature springs 33 and 51 of the switch d^{10} and in the event that this switch were busy the 35 starter wire would be still further extended over extended starter wires d^{65} and d^{64} of the switch d^{10} which will lead into the starter wire from the next two succeeding groups in the same manner as shown in the c and d groups.

40 In order that a second switch may not be started by the closing of a line in any group while the finder switch assigned to that line is picking up the line terminals provision is made for holding open the 45 starter extension lines at the contacts 62 and 63 during the time the switches are in operation and this is accomplished by the relay a^{62} which is a slow relay; that is, one which is energized when it receives current 50 but is slow in releasing and will hold up its armature during a series of impulses. This relay is in a branch circuit of the motor magnet circuit extending from point 45 by wire 66 to relay 61, battery and ground so 55 that it is energized simultaneously with the energization of the motor magnet 19 and if the motor magnet is successively energized by fairly rapid current impulses passing through it the same impulses passing 60 through relay a^{62} will cause this relay to hold up its armature springs and thus hold open the starter extension wires 64 and 65 until these impulses cease when the switch 65 is brought to rest, relay a^{62} deenergized and the starter wires extended.

To avoid complication the circuits for continuing the operation of the respective switches and some of the various other circuits are omitted in Fig. 2 and it now remains to briefly describe the circuit for continuing the 70 operation of the switch until the calling line is picked up which is shown in Fig. 3. In this figure I have shown three subscribers' lines in each of two groups; that is, in the a group and b group these lines are indicated by 1^a 2^a 3^a and 1^b 2^b 3^b , each of the lines and mates in the a group extend to terminals in the upper bank of contacts, while each of the lines and its mate in the b group extend to similar terminal contacts 80 in the lower bank of the switch a^{10} and these lines are provided with the line relays a^1 , a^2 , a^3 for the a group and b^1 , b^2 , b^3 for the b group as hereinbefore described. The armature spring 30 of each of these relays has in 85 addition to the starter wire contact 31, a back contact 67 which is connected by wire 68 to a terminal a^{69} in the upper bank or b^{69} in the lower bank. These terminals a^{69} or b^{69} of each of the upper and lower banks of each 90 switch are therefore normally grounded through the grounded spring 30, back contact 67, and wire 68. Two of the wipers a^{70} and b^{70} one in the upper bank and one in the lower bank are adapted as the switch is 95 moved to contact successively with the terminals a^{69} and b^{69} of the respective lines and these wipers are connected by wires a^{71} and b^{71} to contacts a^{72} and b^{72} in the auxiliary switch a^{11} with which the auxiliary switch 100 wiper a^{73} contacts in the first or second position. Wiper a^{73} is connected by wire 74 to point 75, to wire 38 which is connected to armature spring 37 of the relay magnet 55. The auxiliary switch wiper a^{73} is therefore 105 in a branch of the circuit which energizes the motor magnet relay 41 so that the closing of the line of any subscriber in group a which results in the energizing of motor magnet relay 41 as before described, also 110 places grounded battery on the wiper a^{73} over the circuit from grounded battery at relay 41, armature spring 40, contact spring 39, wire 38, to point 75, wire 74, and auxiliary switch wiper a^{73} . As soon as the main 115 switch has taken its first step, therefore, by energizing and deenergizing the motor magnet 47 as before described and the breaking of the starting circuit, the motor magnet relay 41 would be subsequently energized over 120 the circuit before described from battery, relay 41, armature spring 40, contact 39, wire 38, connecting point 75, wire 74, auxiliary switch wiper a^{73} , contact a^{72} , wire a^{71} , main wiper a^{70} , terminal contact a^{69} , wire 68, contact 67, and grounded armature spring 30 125 providing the said armature spring 30 is in its normal position. This will cause the motor magnet 47 to be energized which will in turn break the circuit of the motor magnet 130

relay 41 which will in turn break the circuit of the motor magnet and cause the switch to take the second step in case the wiper a^{70} lands on a contact a^{69} which is grounded over the wire 68 and spring 30, the switch will therefore continue to operate by impulses thus received. If, however, the line relay a^1, a^2, a^3 of either of these lines has been energized, its armature spring 30 will have pulled up so as to break the grounded circuit for its terminal 69 at contact 67, the motor magnet relay will thus fail to receive current and the switch will thus stop. In case a call should have originated in the b group thus grounding the starter wire b^{32} , the relay 55 will have been operated as before described, thus changing the armature spring 37 from back contact 36 to contact 56 which would connect starter wire b^{32} to the motor magnet relay circuit as before described and would, by moving the auxiliary switch, move the auxiliary wiper a^{72} , thus leaving the circuit of the main switch wiper a^{70} open at contact a^{72} and closing the circuit of the main wiper b^{70} at contact b^{72} so that the switch would continue to operate until it finds a non-grounded terminal b^{69} in the lower bank. The subsequent opening of the operating circuit of a line in group a at contact 67 by energizing a line relay in that group would have no effect upon the operation of the switch since the operating wiper a^{70} pertaining to that bank would be disconnected or connected to an open circuit over which no current impulses could be received or transmitted until the auxiliary switch had been returned to its normal position.

I have thus described the method of starting and continuing the operation of the switch until the subscriber's line which has been closed at the switch hook is found or picked up by the switch. It now remains to describe how the main lines or talking circuits are connected through to another switch and the operating circuits disconnected when the switch comes to rest upon the calling subscriber's line terminal.

Fig. 4 shows the circuit for cutting out the operating circuits. The circuit of each line relay a^1, b^1 , etc., passes through circuit breakers b^6, b^7 controlled by the cut-out relays a^8, b^8 , so that when these relays are energized the armature of the relays operate the circuit breakers a^6, a^7 and b^6 and b^7 and break the circuits of the line relays, a^1 and b^1 , thus taking these relays off of the main line or talking circuit formed by wires $1^a, 1^b$ which extend through to their terminal contacts in the switch bank. The means for energizing the cut-out relays a^8 and b^8 are as follows:—One side of each of these relays is connected to battery and ground as indicated in Fig. 4. The other side of the relay a^8 is connected by wire a^{76} to terminal a^{77}

in the upper bank of the switch while relay b^8 is connected by wire b^{76} to the contact b^{77} of the lower bank. These contacts are adapted to be engaged by the wipers a^{78} and b^{78} as the wipers are advanced over the contacts and these wipers are connected by wires a^{79} and b^{79} to terminals a^{80} and b^{80} in the auxiliary switch a^{11} , the terminal a^{80} being normally engaged by the wiper a^{81} which is in turn connected to wire 82, contact 83, armature spring 84, wire 85 to ground. The armature spring 84 is controlled by relay 86. This relay 86 is a slow relay and is adapted to be energized over the circuit from grounded battery, relay 86, wire 87, contact 88, armature spring 89 of relay 41, wire 90, contacts 91 and 92 to ground, when the motor magnet relay 41 is energized. Relay 86 is retained energized so long as circuit impulses are passing through the motor magnet relay 85 thus holding the grounded connection for wiper a^{81} open at contacts 83 and 84. So soon as the impulses cease the slow relay 86 becomes deenergized, the contact 84 is closed, thus putting ground on the side switch wiper a^{81} , which will in turn ground terminal contact a^{77} through the wire a^{79} and wiper a^{82} and thus operate the cut-off relay a^8 . This will take place only when the main switch wiper comes to rest sufficiently long to permit the slow relay 86 to become deenergized. In case the call has originated in the b group the auxiliary switch a^{81} will, upon the first impulse in the starter wire, move to contact b^{80} in which case the ground connection through contacts 84 and 83, wire 82 and wiper a^{81} will be transferred to the contact b^{80} and thence over the circuit wire b^{79} , switch wiper b^{78} , terminal b^{77} , wire b^{76} to cut-off relay b^8 .

The first two terminals in each of the banks is reserved for the line and mate of each subscriber's circuit, as are also the first two wipers of each bank, and these wipers are connected (as indicated by the heavy lines in Fig. 5) to the terminals 93, 94, 95 and 96 of the auxiliary switch a^{11} , the auxiliary switch wipers 97 and 98 being connected by wires 99 and 100 to armature springs 101, 102 on the relay 86. These springs being normally engaged with back contacts 103, 104 of wires 105 and 106 which lead to the next switch, these wires 105 and 106 and connections just described form a tie between the wipers (reserved for the main line or talking circuit) in the line or finder switch and corresponding wipers in the next or first selector switch, and this tie is held open at contacts 101, 102, 103 and 104 so long as the slow relay 86 is energized, which is as long as impulses are passing through the operating relays for operating the switch wipers to the proper terminals. In this case, as before, it will be noticed that the switch wipers for the upper bank are

normally in circuit with the auxiliary switch wipers and through them to the tie wire leading to the next switch. But in the event that a starting impulse comes from the other bank it transfers the auxiliary switch wipers to the other set of contacts and thus brings the line and mate of the second bank over the auxiliary switch wipers 97 and 98 and through the contacts 101, 102, 103, and 104 to the wires 105 and 106 so that these lines in either case will be held open so long as the switch is being operated but will be immediately closed through to the next switch so soon as the finder switch stops on the calling line and the slow relay 86 drops back.

The release circuit from the first selector or subsequent switch is shown at 107 and passes through back contact 108 armature spring 109, on the slow relay a^{62} thence by wire 110 to spring 111 on the off-normal switch and whenever the switch is in an advanced position this spring engages contact 112 which is connected by wire 113 to the release magnet 114 thence to battery and ground. A branch line 115 leads from 113 to the auxiliary switch release magnet 116 to battery and ground so that an impulse over the wire 107 would operate both release magnets 114 and 116 and cause the switches to be released and this release circuit is held open at the contact 108 and 109 while the switch is operating by slow relay a^{62} . The release magnet 114 is also provided with an armature spring 117, which, when the magnet is energized, closes on contact 118 which is connected by wire 119 to electrical contact 120 in the circuit for the slow relay 86, so that when the release relay is energized it also energizes the slow relay 86 and thus opens the main or talking circuit while the main switch wipers are returning over the terminal contacts to their normal position.

It will be seen that if a call originates in the upper bank, this call passes through the switch by operating the same in a manner similar to that heretofore described for the other bank. The upper bank wipers are cut out and the lower bank wipers are cut in and the switch then performs its operation in connection with the lower bank of contacts in substantially the same manner. In either case the starter wires relating to both the upper and lower banks are extended to other switches so that calls originating in either of these groups relating to these banks would be transferred to other switches.

It will be noted that the circuit for the slow relay 86 passes through contacts 91, 92, which are controlled by relay 47 which is also a slow relay and that this relay 47 is in a branch of the circuit for the motor magnet being connected to grounded battery G B and by wire 120 to wire 46 at point 45 so that this relay is energized whenever the motor magnet is energized which takes place

after the energization of the motor magnet relay 41 and the slow relay 86. The energization of the relay 47 opens the circuit for the relay 86, but inasmuch as the relay 86 is slow it does not immediately drop back and as the motor magnet is immediately deenergized and the switch advanced one step, the slow relay 86 finds ground through the operating circuit of the switch which includes the fourth wiper of the main switch, as heretofore described, and remains energized so long as the switch continues in operation. As soon as the switch stops by the failure of the fourth wiper of the series to find ground the relay 41 is deenergized and the relay 86 also becomes deenergized, which in turn opens the circuit for the relay 47 which becomes deenergized and in turn opens the circuit for the relay a^{62} so that the armature of each of these relays falls back in the order mentioned. The deenergizing of the relay 47 closing contacts 91, 92 with the switch in its advanced position puts ground from the ground wire G, as before described, onto the fourth wiper of the main switch which in turn grounds the contact upon which it is resting and also multiples of said contacts in each of the other switches of this group thus making this particular contact busy and preventing any connector switch from selecting this line.

In Figs. 2 and 3 I have shown the slow relay a^{62} as in a branch circuit of the motor magnet controlled by the contacts 42 and 43. In Fig. 5 this relay is shown in a circuit controlled by the slow relay 47, which in this case is put in the branch circuit of the motor magnet and which extends from point 45 by the wire 121 to relay 47 to ground and battery. The circuit for the relay a^{62} extending from ground wire G, through contacts 43, 42 wire 66, relay a^{62} to grounded battery. The operation is substantially identical except the additional relay 47 is interposed for other purposes and this relay in Fig. 5 is made to control the relay a^{62} instead of having it controlled direct from the motor magnet circuit.

Having thus described my invention, I claim:

1. In a switch for automatic exchanges, a series of terminal contacts arranged in banks and a series of wipers supported on a common shaft and arranged in sets, one set for each bank, each of said wipers adapted to form a link in a circuit including one of said terminals, means for operating the shaft carrying the wipers by current impulses, and means operated by said current impulses for disconnecting one set of said wipers and connecting another set of said wipers.

2. In a switch for automatic telephone exchanges, a series of contacts arranged in banks and a series of wipers, one set for each

bank, means for causing the wipers to move step by step over said contacts by current impulses, an operating circuit for each of said banks, and means for disconnecting one of said sets of wipers and connecting another set of wipers by the current impulses passing through said operating circuits.

3. In an automatic switch, a plurality of banks of terminals arranged in sets and sets of wipers, one set for each bank operated by current impulses, terminals in each of said banks connected to subscribers' lines, an extension circuit through said switch for said subscribers' lines and means operated by said current impulses for automatically connecting said extension circuit to the line wipers traversing the bank to which a subscriber is connected whenever said subscriber's line is to be connected through said switch for conversation.

4. In a switch for automatic exchanges, a plurality of sets of bank contacts and sets of wipers one for each bank, means for operating the said wipers by current impulses over said bank terminals, a main line or trunk circuit leading from said switch, and means for connecting one set of wipers to said line or trunk and disconnecting the other set of wipers therefrom by the current impulses for operating said wipers.

5. In a switch having sets of terminals for subscribers' lines arranged in a plurality of banks, sets of wipers, one set for each bank, a line or trunk circuit connected to said switch and means for connecting said line or trunk circuit to wipers in either set, operating means for causing said wipers to move step by step over said terminals by current impulses, which are also adapted to establish a connection between said line or trunk and one set of wipers and disconnect the same from the other set of wipers.

6. A finder switch for automatic telephone exchanges, having a series of contacts arranged in banks and a set of wipers for each bank, means for operating the wipers by current impulses transmitted through contacts in one of the banks, and means for forming an electrical connection with a set of wipers corresponding to the contact over which the current impulses flow and electrically disconnecting the other set of wipers.

7. In a finder switch having a plurality of banks and sets of wipers one for each bank, means for operating the wipers by current impulses transmitted over contacts in one of the banks, means operated by said impulses to electrically connect one set of wipers and disconnect the others and also for extending the lines over which the starting impulses are transmitted to other switches as described.

8. In a switch for automatic exchanges, a series of terminal contacts arranged in a plurality of banks, subscribers' stations con-

nected to said terminals in each bank, a series of wipers arranged in sets, one set for each bank, means for operating the terminals step by step over said contacts by impulses passing through contacts in one of said banks, an auxiliary switch having wipers corresponding to the wipers relating to each bank and means for connecting the wipers to said auxiliary switch to the main wipers relating to the bank over which the impulses are passing and disconnecting them from the wipers of other banks.

9. In a finder switch for automatic exchanges, a series of terminal contacts arranged in banks, multiple wipers, one set for each bank, subscribers' stations arranged in groups with different groups in different banks, a starter wire from each group to each switch, and means connected with the starter wire for shifting the connections from one set of wipers to another.

10. A switch as described, terminal contacts arranged in groups and a series of switches less in number than the number of terminals and multiple connections from the different terminals to the different switches, a plurality of banks of terminals and sets of wipers and sets of starter wires, one for each bank and means connected with one or more of the starter wires to shift the connections with the wipers as and for the purpose specified.

11. In an automatic switch having a series of terminal contacts arranged in banks and wipers for each bank, means for electrically disconnecting one set of wipers and electrically connecting another set as the switch is operated, and means for restoring the normal condition of the wipers when the switch is restored to normal position.

12. In a switch such as described having a plurality of sets of banks and a plurality of sets of wipers with means for electrically connecting one set of wipers to correspond with the bank to be selected, electromagnetic means for operating said switch and a release magnet for restoring said switch to normal condition, and means associated with said release magnet for also restoring the electrical connection with the switch wipers to normal condition when the release magnet is operated.

13. In a switch such as described, having a plurality of banks, and a plurality of sets of wipers for operating therewith, subscribers' stations arranged in groups, one or more groups being connected to one bank and one or more groups connected to the other bank, two starter wires, one for each group in each bank, and means for sending an initial impulse over said starter wire, an auxiliary switch adapted to make and break an electrical connection with said switch wipers, and means in one or more of said starter wires for operating said auxiliary

switch to establish an electrical connection with one set of wipers and break the electrical connection to the other set.

14. In a switch such as described, having a plurality of banks, and a plurality of sets of wipers for operating therewith, subscribers' stations arranged in groups, one or more groups being connected to one bank and one or more groups connected to the other bank, two starter wires, one for a group in each bank, means for sending an initial impulse over one of said starter wires, an auxiliary switch adapted to make and break an electrical connection with said switch wipers, and means in one or more of said starter wires for operating said auxiliary switch to establish an electrical connection with one set of wipers and break the electrical connection to the other set, a release circuit for releasing the switch and a branch of said release circuit adapted to operate the release for the auxiliary switch.
15. In a switch such as described, having a plurality of sets of banks with a plurality of sets of wipers, means for establishing an electrical connection to one set of wipers and breaking the connection with another set of wipers, two or more starter wires, one for each bank and means in one of said starter wires for effecting the electrical connection with said switch wipers, and means in said switch for extending both of said starter wires to another switch after the switch has been operated to establish a connection in one of the banks.

16. In a switch such as described, having a plurality of sets of banks with a plurality of sets of wipers, means for establishing an electrical connection to one set of wipers and breaking the connection with another set of wipers, two or more starter wires, one for each bank and means in one of said starter wires for effecting the electrical connection with said switch wipers, and means in said switch for extending both of said starter wires to another switch after the switch has been operated to establish a connection in one of the banks, and other means involving a slow relay for holding said starter wire extensions open until the switch has ceased operating in making a bank connection.

17. In an automatic switch having a series of terminal contacts arranged in banks and wipers arranged in sets, one set for each bank, a trunk circuit normally connected with one set of wipers and means for electrically disconnecting one set of wipers from said trunk and electrically connecting another set from said trunk as the switch is operated, and means for restoring the normal condition of the wipers when the switch is restored to normal position.

In testimony whereof, I have hereunto set my hand this 31st day of October 1911. 65
